UNITED STATES PATENT OFFICE

104,647

DESIGN FOR A MILK CAN COVER

François Bastinck, Jersey City, N. J.

Application December 21, 1936, Serial No. 66,668

Term of patent 3½ years

To all whom it may concern:

Be it known that I, François Bastinck, a subject of the Queen of Holland, residing at 135 Prospect St., Jersey City, in the county of Hudson and State of New Jersey, have invented a new, original, and ornamental Design for a Milk Can Cover, of which the following is a specification, reference being had to the accompanying drawing, forming part thereof.

Figure 1 is a top plan view of a milk can cover showing my new design, and

Figure 2 is a side elevation thereof.

I claim:

The ornamental design for a milk can cover as shown.

FRANÇOIS BASTINCK.
